UNITED STATES PATENT OFFICE.

CHRIS ANDERSON, OF LEEDS, ENGLAND.

APPARATUS FOR WORKING ELECTRIC TRAMWAYS.

SPECIFICATION forming part of Letters Patent No. 586,652, dated July 20, 1897.

Application filed February 13, 1895. Serial No. 538,285. (No model.) Patented in England July 13, 1894, No. 13,550.

To all whom it may concern:

Be it known that I, CHRIS ANDERSON, engineer, a subject of the Queen of Great Britain, residing at Lane House, Jack Lane, Hunslet, 5 in the city of Leeds, in the county of York, England, have invented certain new and useful Improvements in Apparatus for Working Electric Tramways, (for which I have obtained provisional protection in Great Britain, 10 No. 13,550, bearing date the 13th day of July, 1894,) of which the following is a specification.

Under the present method of working electric tramways it is necessary to have motors 15 of sufficient capacity to surmount the hardest part of the road, although that part may be but a very small proportion of the whole length of the road. This is a great drawback because of the additional weight which the 20 tram-cars have to carry, which becomes aggravated when the car is required to travel uphill, besides adding greatly to the expense of working. To overcome these difficulties and use only motors which are sufficient for 25 the major part of the length of the road, I propose to supplement the motors carried by the cars by the use of cable haulage—that is to say, by the use of underground traveling cables placed under the roadway in those 30 places where additional power is required. These haulage-cables are laid and connections between them and the cars made in such manner as is common to underground haulage-cables, but they are worked by electricity 35 by means of motors driven by the same current as that by which the car is propelled. Each haulage-cable is set in motion by the car as it comes to the place where the additional power is required, and the motion ceases 40 when the additional power is no longer required. For the purposes aforesaid I mount upon the car a switch, to be operated by the driver, by means whereof a part of the electric current from the conductor or cable driving 45 the car may be diverted so as to pass through suitable connections into a separate conductor or wire used solely for the purpose of driving the motors by which the haulage-cable is set in motion.

50 Such being the nature of my invention, I now proceed to describe more fully, by means

of the accompanying drawings, the means by which I carry the same into practical effect.

Figure 1 shows in vertical cross-section, on the line *a b*, Fig. 3, looking at the back of 55 the car, a portion of the tram-car frame with the wheels of the car and the motor, with the two ramps and contact-brush beneath, and also a section of the roadway supporting the car, showing the rails, the haulage-cable conduit with the slot, and, in dotted lines, the box containing a peg mechanism, showing the pegs up. Fig. 2 is a vertical cross-section of the mechanical and contact pegs on the line *c d*, Fig. 4, looking toward the car as it approaches, and showing also in cross-section the contact-brush and ramp, and showing also the method of forming connection between the contact-peg and the electric-supply conductor below, and also the method of forming connection between the mechanical peg 65 and the haulage-motor cable below. Fig. 3 is a side elevation of a tram-car as seen ascending an incline, with the gripper shown descending from the front of the car down 70 through the slot in the roadway and in contact with the haulage-cable, showing also the haulage-cable and haulage-motor. Fig. 4 is a plan of the underframe of a tram-car, also of the roadway, with three mechanical boxes, 75 also the slot-rail for contact with the haulage-cable, showing also the electrical connections from the switchboards to the car-motor, to the contact-brush, and to the ramp.

The same letters and numbers refer to the 85 same parts throughout the drawings.

A A represent the tram-car as shown in vertical cross-section and side elevation in Figs. 1 and 3, respectively, and the underframe only, as shown in Fig. 4.

A' A' are the drivers' platforms at the ends of the car.

A² A² are the dashboards.

1 1 are the tram-car wheels.

2 is the car-motor.

3 3 are the ramps, one for each way the car runs.

4 is the contact-brush attached to the car.

5 is the mechanical peg, whose upper end slides through the box-cover 10' and its lower end in the socket 17, Fig. 2. The mechanical peg is mounted on a stud or cross-arm 6, on

the other end of which the contact-peg 7 is mounted.

8 is the roadway, 9 the tram-rails, and 10 the box containing the pegs and their accompanying mechanism, and 10' is the box-cover.

11 is the haulage-cable conduit sunk in the roadway, and 11' is the slot in the conduit-cover.

12 is the haulage-cable.

10 The contact-peg 7 is provided with a rod 5' for the purpose of forming contact with the electric-supply conductor 14 by means of the C-spring 5², sliding in the socket 13, connected with the said supply-conductor.

15 The contact-peg 7 (shown in detail in Fig. 2) is so constructed as that its sides on the parts which pass through and in contact with the box-cover are insulated from the top, which comes into contact with the contact-brush, and its sides are also insulated from the rod 5'. When the peg is down it is out of connection with the electric-supply conductor.

The mechanical peg 5 is made hollow and 25 incloses a central rod 18 for the purpose of forming contact when required with the electric-haulage-motor cable 20 by means of the spring 19, projecting through a slot formed in the side of the mechanical peg. The sides of 30 the mechanical peg are insulated from the central rod 18 in like manner as the contact-peg.

21, Fig. 3, is the haulage-motor, and 22 is the gripper, preferably one at each end of the car, for gripping onto the haulage-cable.

35 23 23, Fig. 4, are switchboards mounted one at each end of the car. Each switchboard is connected by a wire 24 to the contact-brush 4 and through it and the contact-peg 7 to the electric-supply conductor. A wire 25 conveys electricity from the switchboard to the car-motor 2, and a third wire 26 is provided 40 capable of being switched into contact with the ramps 3 3, (one at a time only, according to the direction the car is to run,) and thereby 45 supply electricity to the haulage-motor cable 20 through the central rod 18 of the mechanical peg.

The action of my electric-tramway apparatus is as follows: When a car comes to a part

of the road where a haulage-cable 12 is laid 50 and it is desired to use it, the driver of the car will drop the gripper 22 so as to engage with the haulage-cable 12 and at the same time switch on the electric current to the haulage-motor cable 20. The electric current will 55 then pass from the electric-supply conductor 14 up through the contact-peg 7, then through the contact-brush 4 to the switchboard 23, then through the wire 26 to the ramp 3 and mechanical peg 5 and down the central rod 60 18 and the spring 19 to the haulage-motor cable 20, and thence to the motor 21 and so set the haulage-cable 12 in motion.

My invention is equally applicable to electric tramways worked by means of overhead 65 wires as to those worked by means of underground wires or cables.

The switchboard is so arranged that when it is desired to use the haulage-cable the same switch will operate to turn the electricity on 70 or off the car-motor and the haulage-motor at the same time.

Electricity for lighting the car may be taken from the same switchboard by the method at present in use.

Having now described the nature of my invention and in what manner the same is to be carried into practical effect, I desire to make known that what I claim as my invention is—

In an electric-tramway system, the combination with a car carrying an electric motor, a contact-brush, a ramp, a switchboard, electrical connections from said switchboard to the contact-brush, motor and ramp, and a gripper, and with an electric-supply conductor, a peg for making electric connection between said conductor and the contact-brush; and a haulage-cable for use as an auxiliary power actuated by an electric motor, of a haulage-motor cable or conductor for said 90 motor; and a peg for making connection between said conductor and the ramp, substantially as described.

CHRIS ANDERSON.
